UNITED STATES PATENT OFFICE.

OLIVER C. GILBERT, OF ST. LOUIS, MISSOURI, ASSIGNOR TO GEORGE EVANS WALKER,
OF ST. LOUIS, MISSOURI.

ELECTRICAL PLUG.

Application filed March 17, 1923. Serial No. 625,878.

To all whom it may concern:

Be it known that I, OLIVER C. GILBERT, a citizen of the United States, residing at St. Louis, in the State of Missouri, have invented 5 certain new and useful Improvements in Electrical Plugs, of which the following is a specification.

This invention relates to improvements in electrical devices for use in connection with 10 wireless telephony.

The object of the invention is to provide a plug for changing the circuits to the head sets or ear phones of a wireless outfit.

One of the particular objects is to provide 15 a device, whereby the double head sets may be connected in series or in parallel as often-times the clearness of the received message depends upon the connections; that is to say, whether in series or parallel.

20 Heretofore it has been the common practice to make these different changes, or connections, by disassembling the plug devices or reassembling the connections. In the present invention these changes of the circuits are quickly made by simply rotating 25 one member of the plug relative to the other.

Broadly it comprises a hand piece in which is threaded a plug device. This hand piece receives the ends of the terminals of 30 the cables and to the threaded plug device is connected the metallic terminals or pin points of the cables, and a second or rotatable piece mounted on the threaded plug device, whereby when the rotatable piece is 35 moved into different positions the electrical connections are changed in the head pieces from series to parallel or vice versa or open as will be fully described.

Referring to the drawings:

40 Fig. 1 is an elevational view of the assembled plug showing the handle or casing member, the plug threaded into the casing and the rotatable member connected thereto.

Fig. 2 is a detail of one terminal of the 45 plug and which serves to secure the parts together.

Fig. 3 is a detail view of the pin and the tubular casing in which the pin is located and serves as the other terminal, these parts 50 represent the two poles.

Fig. 4 is a detail sectional view on the line 4-4 of Fig. 1 showing the interior structure of the casing and illustrating the four cables therein.

Fig. 5 is a detail view of the bushing in 55 the rotatable member.

Fig. 6 is a detail view of the threaded plug device on the line 6-6 of Fig. 8 showing one of the tubular insert pieces and one of the spring actuated plungers.

Fig. 7 is a detail view of the rotatable member separated from the plug part.

Fig. 8 is a detail view of the inner end of the threaded plug device showing the ends 60 of the bushings into which the terminals of the cables are inserted.

Fig. 9 is a top plan view of the opposite end of Fig. 8.

Fig. 10 is a bottom plan view of the rotatable member showing the kidney bean 70 shaped metallic contacts embedded in the insulating material.

Fig. 11 is an outer end view and side elevational view respectively of the rotatable member.

Fig. 12 is an inner end view of the rotatable circuit changing member. Fig. 13 is a side elevational view of the removable plug device and the rotatable member assembled and in the position which shows the connections in Fig. 18.

Fig. 14 is a detail sectional view of the plug device which receives the pin point contacts of the cables also showing the embedded electrical connection between the 85 centrally located threaded bushing of the plug device and a tubular member to which one of the cables is connected.

Fig. 15 is an enlarged detail view of one of the cables and one of the conical shaped 90 springs located in one of the bushings.

Fig. 16 shows the arrangement of the circuits when the double head sets are arranged in series.

Fig. 17 shows the connection when the rotatable part connects one of the double head sets and a loud speaking telephone in parallel.

Fig. 18 shows the connections when only 100 one of the head sets is in use.

Fig. 19 shows the connections when the loud speaking telephone is in use and the double head set is cut out or idle.

Fig. 20 is a longitudinal sectional view of 5 a modification in which the threaded sleeve is omitted, and the internally located bushing of insulation on the connecting rod.

Fig. 21 is a detail top view of the rotatable disk.

10 Fig. 22 is a bottom plan view of the rotatable disk showing the kidney bean shaped contact pieces, and the locking depression in one of the pieces.

15 Fig. 23 is a side elevation of the rotatable disk with part broken away substantially on the line 22—22 of Fig. 21.

Fig. 24 is a bottom plan view of the plug.

19 Fig. 25 is a sectional view on the line 25—25 of Figs. 24 and 26 and

20 Fig. 26 is a top plan view of the threaded plug.

Referring to the drawings in detail:

25 1 designates the handle portion of the complete plug which is formed with an opening to receive the threaded bushing member 2 and through which the cables, four of which are shown, pass as indicated by the numerals 3, 4, 5 and 6. Each of these cables is formed with the usual woven wire 30 core indicated at 7 and connected to the woven wire core are the metallic terminal tips or points 8, one of which is shown. The opposite end of the handle member 1 is formed with an internally threaded end part 35 9 for receiving the threaded plug device or member 10 which is also composed of some suitable insulating material. Located within this plug member are the four metallic tubular members 11, 12, 13 and 14, an en- 40 larged detail of one being shown in Fig. 15. Fig. 6 shows also the tubular member 14 in section. The inner ends of these tubular members project beyond the inner end 15 of the plug member 10 and each of them are 45 formed with an opening 16 through which passes one of the metallic terminals 8 of the different cables. These metallic terminals are slightly tapered and engage the inner surfaces of the coils of the conical shaped 50 spring 17, a detail of which is shown in Fig. 15. The diameters of the inner ends of these coils is larger than the outer ends, as shown, whereby the tapered metallic terminal 8 will form perfect electrical connection. The 55 coils of the springs 17 are normally under compression, their outer ends engage the cylindrical pins or plungers 18, four of which are employed as shown in Fig. 13.

60 It will be observed that the tubular shaped members 11, 12, 13 and 14 are each formed with a ledge or angular surface 11', 12', 13' and 14' against which the springs 17 bear, the surface 14' being clearly shown in Fig. 15. The springs serve to force the plungers 65 or contact pieces 18 normally outward. The

contact pieces 18, while being shown as spring pressed plungers, may consist of any equivalent type of contact members, and, in the present showing are shown as being four in number, are positioned on an arc 70 respectively, and points substantially 72° apart, there being 144° remaining to complete the circle. While this arrangement of contact members is shown in this embodiment of the invention, it is understood that 75 the invention is not confined to this arrangement because other arrangements may be made to produce substantially the same results, and to affect additional combinations or circuits. 80

Located in the centrally arranged opening 19 of the threaded plug member 10 is the internally threaded bushing or sleeve 20. This bushing is formed with an extension portion 20' which is electrically connected 85 to the tubular member 14, see Fig. 14.

21 is a member composed of insulating material that is rotatably mounted on the plug member 10. The upper or outer end of the member 21 is shown at the left of Fig. 11 90 and the inner end of this member is shown in Figs. 10 and 12, which is provided with two insert contact plates 22 and 23 which are engaged by the plungers 18. The angular distance or extent of plates 22 and 23 is 72° 95 which is also the angular distance, or spacing, of the plungers 18, as indicated in Figs. 9, 16, 17, 18 and 19. The plates 22 and 23 are spaced apart between one of their ends approximately 72° and between the other 100 ends approximately 144°. 23' designates a depression in the plate 23 which receives the end of one of the plungers 18 when the rotatable member 21 is turned about the axis. 105

Located on the plug member 10 is an index mark 24, and located on the edge of the rotatable member 21 are the letters P (parallel) S (series), and the numerals 1 and 2, the numeral 1 referring to the plug when connections are made to two double head sets, or to one double head set and a loud speaking phone, the other being idle. This connection is shown in Fig. 18, the number "2" connection is shown in Fig. 19. 110

Referring now to the means for securing the parts together, 25 designates a tubular member which is formed with a reduced portion 25' which is threaded at 26. The threaded part engages the threads of the sleeve 20. 115

27 designates a sleeve (see Fig. 5) which is placed in the part 21 and receives the reduced part 25' of the member 25. 28 (see Fig. 2) is a pin which is formed with a knob or spherical end 29, and a shoulder 29' and a threaded end 30. The pin 28 when assembled passes through the tubular member 25, its shoulder portion 29' engages a ring piece of insulation 31, and its inner 120 end passes through a ring or sleeve of in- 125

sulation 32, and these two rings insulate the pin 28 from the sleeve 25. The threads 30 of the pin 28 engage the threads 32 of the plate 33 (see Figs. 6, 8, 9 and 14) and serve to make electrical connection therewith and with one of the tubular members in which the conical springs 17 are placed. The threads 26 of the sleeve 25 serve to retain the parts 10 and 21 together and to permit the part 21 to turn on the sleeve 27. 34 designates a ring for securing the end of the cable thereto in the usual manner to prevent the cable from being drawn away from the plug.

15 Referring now to the operation of the device, looking at Fig. 16 the part 21 is rotated so that the letter "S" thereon registers with the reference line 24 on the fixed part 10, the current is then in series with 20 the two head sets 35 and 36 as shown, it enters by the knob 29 of the pin 28, to plate 33, through the plate to the cylindrical member 14, plunger 18, plate 23, cable 3, phones 35, cable 4, plate 22, cable 5, phones 36, cable 6, plunger 18 to the sleeve 25 which is the other terminal. When the part 21 is turned through 72° so that the letter "P" is opposite the reference line 24 (see Fig. 17) the head set 35 and loud speaking 30 phone 37 are in parallel connection through the cables 3, 4, 5 and 6. When the part 21 is turned so that the numeral 1 registers with the reference line 24 (see Fig. 18) only one head set is then connected, the other being idle. When the part 21 is turned so that the numeral 2 registers with the reference line 24 the loud speaking telephone 37 is then idle or cut out and the head set 36 is connected.

40 The current through the cables 3, 4, 5 and 6 head sets, plungers 18, plates 23 and 24 is clearly indicated by the arrows.

From this description it will be seen that I have provided a telephone plug used in 45 telephone systems and in radio telephone apparatus for the purpose of effecting a connection between one circuit and another circuit and thereby permitting the selective coupling of circuits.

50 In particular, this invention relates to an improvement in such circuit connecting plugs; all former constructions having to do solely with the connecting or disconnecting of fixed circuits wherein the circuit wires are attached to the plug terminals in such manner that only one path is open to the current or currents dealt with.

In my invention there is incorporated 60 with and within the plug an arrangement of switches, whereby the same plug may be used as a means of controlling the various circuits to which it may be connected.

As an illustration of a use of my invention there may be cited the application to 65 radio telephone head sets wherein hereto-

fore it has been impossible to readily change the circuit from series to parallel when one head set is used, or to accomplish the same object with more than one head set without the use of a specially wired series of jacks 70 and in the former case it could only be accomplished by the use of two head set cords and necessitated the changing of the terminal wires whenever it was desired to change the circuit from series to parallel or from 75 parallel to series. In my invention it is required only that the switch within the plug be thrown to change from series to parallel or from parallel to series.

Referring to the modification shown in 80 Figs. 20 to 26.

The part 10 is provided with a plate 40 which is located in the groove or depression 41, the groove being of such depth that the plate 40 does not come out flush with the 85 surface 42 of the part 10; by having the plate 40 of less thickness than the depth of the groove 41, a ridge or edge 43 is provided which serves as a centering rim for accurately locating the inner end 44 of the 90 sleeve 27 on which the part 21 turns. The threaded sleeve 20 shown in Fig. 6 is omitted in this modification. In order to secure the rotatable part 21 to the plug part 10 the threaded part 30 on the end of the 95 rod 28 engages the threads of the plate 33, as before. The plate 40 therefore serves as an electrical connection between the tubular sleeve 27 and the tube 25. The plate 40 is connected to one of the tubular members as 11 (see Fig. 26). The opening 45 through the insulating material of the part 10 is smaller than the opening 40' in the plate 40 whereby the rod 28 is insulated or spaced from the plate 40 as shown in the 105 assembled sectional view in Fig. 20.

The plate 33 at the inner end of the part 10 is formed with a struck-up portion 46 having an opening 46' to receive the loose end of the cable in the usual way. This 110 struck up part is for the same purpose as the part 34 shown in Fig. 8. The plate 33 also provides an electrical connection with one of the tubular members as 14.

An important feature of the modification 115 shown in Figs. 20 to 26 is that the adjacent surfaces of the parts 10 and 21 are beveled as indicated at 10' and 21', whereby the reference or locating numerals 1 and 2 and the letters P and S can be readily seen by the 120 user of the plug, also the outer end of the part 21 is beveled as indicated at 21' whereby the numerals 1 and 2 and the letters P and S can be readily seen by the user. The electrical connections described above and 125 shown in Figs. 16, 17, 18 and 19 are the same in this modification.

What I claim is:

1. A plug device adapted for radio receivers comprising a body to which a plurality 130

of electric circuits may be electrically attached and including a plug extending therefrom, and movable means on the device electrically interposed between the plug and 5 said circuits for changing the electrical connections from series to parallel, or vice versa.

2. A plug device comprising a body to which a plurality of conductors may be electrically attached, and including a plug extending therefrom, a rotatable switch member on the plug electrically interposed between the plug and said conductors, and means on said member for changing the 10 electrical connections with said conductors from series to parallel, or vice versa.

3. A plug device adapted for radio receivers comprising a plug body to which a plurality of circuits may be directly attached, a switch member on the plug body electrically interposed between the plug and the circuits, and cooperative means on said member and plug for changing the electrical connections between the circuits from series 20 to parallel, or opening all but one of said circuits, or vice versa.

4. In a jack plug, a body insertable into a jack and having means thereon to which a plurality of circuit conductors may be attached certain of said circuit conductors being electrically connected with the plug, a 30 rotatable switch member on the plug electrically interposed between the plug and said conductors, and means on said member engageable with said conductors for establishing and changing the electrical connections between said conductors from series to parallel, or to eliminate any of said circuits, or vice versa.

40 5. In a jack plug, a body having a plug fast thereto, and means to which a plurality of circuit conductors may be attached, contact members electrically associated with said means, a movable switch member on the plug electrically interposed between the 45 plug and said contact members and engageable with the latter, and means on said switch member cooperating with the contacts for changing electrical connections between said contacts and said plug from series to parallel, or open any of said circuits, or vice versa.

6. A plug for the purpose described, comprising an electric plug connector, a plurality of spring pressed plungers mounted on said plug, means for electrically connecting said plungers with conductors, a part rotatably connected to the plug and having contact plates thereon and of a length to span 55 the plungers, the arrangement of the plungers and plates being such that when the rotatable part is turned the connections to the conductors may be changed from series to parallel or vice versa, or one of the circuits opened.

7. A combined switch and plug device for the purpose described, comprising a plug having electrical conducting parts, a plurality of terminals on the plug for electrical connection with conductors, at least two of 70 said terminals being electrically connected to the plug to complete a circuit there-through, a member rotatably connected to said plug, contact means on the member for making selective electrical connections with the terminals, said contact means and terminals being so constructed and arranged that a plurality of circuits may be selectively available or may be combined, when the member is rotated, to form a series or parallel connection of the conductors.

8. A combined connector plug and switch device, comprising a handle portion, a plug having electrical conducting parts, a plurality of tubular members on the handle and formed with one end partially closed to form a shoulder, springs in said members and retained by said shoulders, plungers engaged by the springs, said partially closed ends of the tubular members being adapted to receive the terminals of telephone cords, a switch member rotatably connected to the said device, and contact plates on the switch to selectively engage the spring actuated plungers, the connecting means between the switch member and said plug forming the electrical terminals of the device.

9. In a combined plug and switch device, a fixed part, terminals therein to receive the ends of a plurality of conductors, a part rotatably connected to the fixed part, the connecting means comprising a tubular member having an electrical connection with the one of said terminals, a pin member passing through the tubular member and having a 100 threaded connection with another of the terminals and insulated from the tubular member, the rotatable part having contact plates normally in electrical connection with the terminals of the fixed part, said plates serving to connect the conductor terminals with relation to each other as series, or parallel 105 or open circuits, when the rotatable member is moved.

10. A combined plug and switch device, including a fixed and a rotatable member, the fixed member having means to receive and retain the conductor terminals and having yieldable contacts thereon spaced at greater and lesser distances apart, the rotatable member having means for forming electrical connection with the contacts of the plug, said contact means being adapted to span the space between certain of the contacts on the plug of lesser distance apart, whereby when the rotatable member is turned the connection may be changed.

11. In a combined plug and switch device, for the purpose described, a part having means for attaching the ends of the con- 115

ductors thereto, movable contact members on said part in electrical connection with the conductor attaching devices and normally projecting beyond the end of the same, a connector plug extending from said attaching part in electrical connection with at least two of said contacts, a member rotatably mounted on said plug, contact plates on the rotatable member and engaging the movable contact devices, the construction and arrangement of the movable contact devices and plates being such that when the rotatable member is turned in either direction the connections may be changed, and means for designating the different positions of the rotatable member.

12. A switch and plug, comprising a member to which a plurality of conductors may be attached, a plurality of spring pressed plungers on said member arranged about an arc and spaced from each other and adapted to have said conductors electrically connected thereto respectively, a tubular member, a switch element rotatable on the latter, one end of said tubular member being positioned at the radial center of said arc and having electrical connection with one of said plungers, a rod passing through said tube and insulated therefrom, said rod having an enlarged end engaging the other end of said tube and its inner end in electrical connection with another of said plungers, and contacts on said switch selectively engageable with said plungers.

13. In a telephone plug construction, the combination of a cable attaching part having a recessed portion, a plate located on the recessed portion of the part, and a tube having one end engaging the plate to provide a bearing for a rotatable member, the plate

being below the surface of the part whereby the recessed portion provides a centering edge for the tube.

14. In a jack plug construction, the combination of a cable attaching part having a recessed portion, a plate located in the recessed portion of the part, a tube engaging the plate for providing a bearing for a rotatable member, the plate being below the surface of the part whereby the recess provides a centering edge for the tube, said member having devices thereon for changing electrical connections, and terminals in said part for engaging the devices. 50

15. In a jack plug construction, the combination of a conductor-attaching part, a member rotatably connected to the part, means for connecting the same together including a plate on the part, a tube engaging one face of said part, and a threaded rod 60 passing through the tube and insulated therefrom, said rod having an enlarged outer end engaging the other end of said tube and its other end connected to said plate.

16. In a jack plug construction, a part adapted to have a plurality of conductors electrically connected thereto, a member rotatably connected to the part, and means for connecting the same together including a tube engaging one face of said part, a rod 70 passing through the tube and insulated therefrom, said rod having one end engaging the tube and its other end secured to said part, the tube and rod serving to provide a plug having electrical connection with at least two of said conductors, and means between said part and rotatable member for changing the electrical connections between the conductors. 75

OLIVER C. GILBERT.
